UNITED STATES PATENT OFFICE.

ABRAHAM S. GOLDSTEIN AND ALEXIS P. DAVIS, OF BALTIMORE, MARYLAND, AS
SIGNORS TO THE FORD DUPLEX TIMER AND ACCESSORIES COMPANY, OF BALTI-
MORE, MARYLAND, A CORPORATION OF MARYLAND.

TIMER.

Application filed February 17, 1923. Serial No. 619,580.

To all whom it may concern:

Be it known that ABRAHAM S. GOLDSTEIN and ALEXIS P. DAVIS, citizens of the United States, residing at Baltimore, in the State of Maryland, have invented certain new and useful Improvements in Timers, of which the following is a specification.

This invention relates to improvements in timers or circuit closers and is particularly directed to a timer device for making and breaking the circuit in an ignition system of an internal combustion engine.

The main object of the invention is to provide an improved timer wherein the ignition circuit for each spark may be closed at a plurality of contact faces and without multiplying wire connections, whereby a closing of the circuit may be assured at one or the other of the faces of each contact device.

Another object of the invention is to provide an improved rotor having a plurality of contact devices together with a series of stationary contacts in the timer, each of said stationary contacts being provided with a plurality of contact faces and one face of a contact being engaged by one rotor-contact device while another face of the same contact is simultaneously engaged by another of the rotor-contact devices whereby a plurality of contact points will be simultaneously provided between the rotor and each timer contact.

A still further object of the invention is to provide a rotor having a side contact and a bottom contact each in electrical connection with the other, and to further provide a stationary structure wherein each contact has a side contact surface and a bottom contact surface, whereby when one contact of the rotor engages the side contact of a stationary contact the other contact on the rotor will simultaneously engage the bottom contact surface of the same stationary contact.

Another object of the invention is to provide an improved construction of rotor for circuit closers wherein a pivotally carried contact of the rotor is so balanced as to maintain a substantially uniform outward pressure regardless of the variations in the centrifugal force set up by the speed of the rotor.

With these and other objects in view, the

invention is illustrated in the accompanying drawing, wherein,—

Fig. 1 shows the improved timer as viewed from the rear or inner contact side thereof,—a portion of the rotor-disk being broken away.

Fig. 2 illustrates the casing of the timer in cross-sectional detail,—the section being taken on the line 2—2 of Fig. 1.

Fig. 3 shows a cross-sectional detail through the complete device,—the section being taken on the line 3—3 of Fig. 1.

Fig. 4 shows an outer face view of the detached contact-carrying disk of insulation.

Fig. 5 illustrates the improved rotor disk and its pivoted contact head in front elevation.

Fig. 6 shows the same in cross-section,—the section being taken on the line 6—6 of Fig. 5.

Fig. 7 shows the detached rotor in edge view, and

Fig. 8 illustrates one of the detached double-face stationary contacts in perspective.

Referring to the drawing the numeral 9 designates the outer end of the timer shaft on which the rotor is rigidly mounted so the latter will revolve and travel through a circular path as the shaft revolves. The construction of this rotor will presently be fully explained.

Around the shaft-end is located a timer-casing which latter has a circular shell 10 with a dome-shaped outer covering 11 from which latter a short nozzle 12, extends. This nozzle opens or communicates with the interior of the dome as clearly shown in Fig. 3 of the drawing so that a set of ignition wires 13, may be passed through the nozzle to the interior of the dome as and for a purpose that will presently be explained.

On the interior of the timer-casing there is provided a circular disk or partition 14 of insulating material, such as fibre, which latter is so positioned as to form a vertical partition which separates the interior of the circular shell 10 from the interior of the dome-part 11.

This partition 14, has a central annular flange 15 which projects rearwardly into the circular shell-part.

The partition 14 has a beveled edge to

snugly fit the dome-part and is held in the dome-part by screws 8 which pass through sleeves of insulation 7 and enter the disk as clearly shown in Fig. 2 of the drawings.

5 The improved timer-contacts shown in Fig. 8 of the drawing, are attached to and carried by the partition 14 and its annular flange 15.

By reference to Fig. 8 of the drawing 10 which shows one of the detached stationary timer-contacts, it will be noted that said device has one contact face 16; another contact face 17 and an arm 18. The contact face 16 is preferably flat, while the face 17 15 is curved and extends at a right-angle with respect to the flat face 16 and the arm 18 is practically a continuation of the face 17 but narrower than the latter.

It will also be noted that the curved contact face 17 projects laterally from the flat contact face in one direction, while the arm 18 projects from the flat contact face in a reverse direction, and that both faces and the arm are formed from a single integral 25 piece of metal.

These timer contacts are each embedded in the partition 14 and its annular flange 15 so that the flat face 16 of a contact will be substantially flush with the straight vertical face of the disk, while the curved face 19 of the same contact will be substantially flush with the outer circumference of the annular flange 15. This means that each 30 timer contact will present two stationary contact surfaces 16 and 17 one of which is at right angles to the other,—the curvature of the face 17 being on the same radius as the outer face or circumference 19 of the annular flange 15 so as to be flush therewith as 35 can be seen in Fig. 1 of the drawing.

From the above explanation it is believed to be obvious that each timer contact has what may be termed a base contact surface 16 and a side contact surface 17 both of 40 which surfaces are integral with the arm 18.

In practice, the disk 14 and its annular flange 15 are molded with the several contacts embedded therein, and in this instance, the arm 18 of each contact passes through 45 the disk and is exposed at the rear or inner face 20 of the disk as shown in Figs. 3 and 4 of the drawing.

The exposure of the arms 18 of the timer contacts at the inner face of the disk enables 50 the ignition wires 13 to be readily attached thereto in the dome side of the timer-casing as shown in Fig. 3.

In the present instance four contacts are provided in the timer-casing and four ignition wires 13 are also provided,—it being 55 necessary to provide but one wire for each timer-contact irrespective of how many contact-faces each contact may have because both faces of the contact are formed from a 60 single piece of metal.

The rotor, which is separately shown in Figs. 5-6 and 7 of the drawing, comprises a circular disk 21 that is carried on a hub 22. This hub snugly fits and is rigidly attached to the outer end of the timer-shaft 9 so that both the hub and the disk will 70 revolve with the shaft.

The diameter of the disk 21 is such that its periphery will lie comparatively close to the inner circumference of the annular shell 10 in which it will revolve, as clearly shown in Fig. 3 of the drawing, and when in place, the disk will travel in a vertical plane at the inner or rear end of the annular flange 15 of the insulator-disk and perform a useful function that will presently be explained.

Near its periphery, the disk carries a tubular stud 23 which latter projects horizontally from one side of the disk and extends outwardly toward the inner side of the insulation-disk 14. This tubular stud forms a socket for a plunger-contact 24 which latter is kept pressed outwardly by means of a coiled spring 25. The position of this plunger-contact 24 is such that as it is carried around by the disk or rotor 21, it will sweep successively over the flat stationary contact faces 16 and over the surface of the insulator disk 14 in which those contact faces are embedded at equally-spaced intervals, and by these several contacts the plunger 24 will close a circuit, through each face 16 as it engages the same.

The stud 23 also serves as a pintle for a rock-frame which latter comprises two flat 100 bars 26 and a cross-bar 27 which connects said flat bars. This frame is mounted on the stud 23 so that its opposite ends may rock and one end of the frame carries a contact roller 28, which is free to revolve 105 with respect to said frame, while the opposite end of said frame carries a weight 29, which latter substantially counterbalances the roller.

This counterbalancing of the two ends of 110 the frame at opposite sides of the pivot-stud 23 is of a decided advantage because when the rotor is revolved the centrifugal force set up would swing the roller end of the frame outwardly whereas it is desired to keep the roller pressed inwardly so it can roll over the curved contact faces 115 17 of the several contacts which are arranged about the annular flange 15 of the insulation disk.

By therefore providing the weight 29 at the end of the frame opposite to the roller end, said two ends on opposite sides of the stud pivot 23, will both be subject to the centrifugal force set up and one end will 120 substantially counterbalance the other.

In operation, however, it is desired that the roller 28 be kept pressed inwardly so as to engage the curved faces 17 of the contacts and to make this certain under all 125

conditions of speed-rotation, a spring 30 is coiled about the stud 23, and has one end engaged by a pin 31 on the rotor disk 21, while the other end 32 of this spring extends 5 under the weight 29, so as to exert an outward pressure on that end of the frame and thereby swing the opposite roller-end of the frame inwardly to keep the roller 28 in against the annular flange 15.

When the rotor is in place on the shaft 9 and the timer casing is placed thereover, the disk 21, as shown in Figs. 1 and 3 will have its plain side (the side opposite that on which the rock-frame is mounted) facing 10 the engine case so that any oil that might flow outwardly along the shaft 9 will be directed laterally over the disk and then thrown from the periphery of said disk against the annular wall 10 of the timer- 15 casing and may then flow down along said wall and escape at the bottom through a small hole 33.

From the foregoing explanation it will be seen that our improved timer provides 20 double contact-faces for each stationary contact and also provides two rotor contacts one of which will engage one face of a contact while the other will engage the other face of the same contact so that a two-point 25 contact is made each time the circuit is closed and a failure to close the circuit at either of those two points of contact will not affect the ignition circuit so long as a

closure is effected at either of those contact points.

Having described our invention, we claim,

1. In a timer the combination with a casing having a plurality of stationary contacts each of which has two contact faces, of a rotor having a rock-frame, a contact carried by said rock-frame means for holding the rock-frame and its contact against outward movement under centrifugal force said rock-frame contact engaging 40 one face of a stationary contact, and a second rotor contact to engage the other face of the same stationary contact.

2. In a timer the combination with a casing having a plurality of stationary contacts each of which has two contact faces, of a rotor disk in said casing, a contact device carried by the disk to engage one face of each stationary contact, a rock-frame also carried by the disk, a contact device on one side of the pivot of the rock-frame to engage the other face of each stationary contact, and means on the other side of the pivot of said rock-frame to substantially balance the same against outward 55 movement under centrifugal force.

In testimony whereof we affix our signatures.

ABRAHAM S. GOLDSTEIN.
ALEXIS P. DAVIS.
